D15-73. OR D13,878 EX

DESIGN FOR ORNAMENTATION OF SEWING-MACHINES.

Design No. 13,878, dated May 1, 1883.

2 SHEETS - SHEET 1

UNITED STATES PATENT OFFICE.

WILLIAM HAEHNEL, OF NEW YORK, N. Y., ASSIGNOR TO CHARLES PALM
AND JULIUS FECHTELER, OF SAME PLACE.

DESIGN FOR ORNAMENTATION OF SEWING-MACHINES.

SPECIFICATION forming part of Design No. 13,878, dated May 1, 1883.

Application filed March 24, 1883. Term of patent 7 years.

To all whom it may concern:

Be it known that I, WILLIAM HAEHNEL, of New York, county and State of New York, have invented a new and original Design for 5 Ornamentation of Sewing-Machines, of which the following is a specification.

This invention relates to a new and original design for the ornamentation of sewing-machines and other articles; and it consists in the 10 novel grouping and configuration of figures hereinafter more fully described.

The accompanying illustrations show in Figures 1 and 2 opposite views of a sewing-machine plate and arm having thereon my new 15 design. Figs. 3 and 4 are enlarged detail views of the ornamentation at the sides of the cloth-plate. Figs. 5, 6, and 7 are enlarged detail views of the ornamentation at the front portion of the cloth-plate. Figs. 8 and 9 are enlarged 20 detail views of the ornamentation at the side and the back and front of the post of the sewing-machine arm. Fig. 10 is an enlarged detail view of the ornamentation at the side of the sewing-machine arm. Fig. 11 is an enlarged 25 detail view of the ornamentation at the top of the arm.

The figures A A, which are situated on the cloth-plate, at the front edge thereof, consist of curving tendrils bearing leaves resembling 30 maple-leaves and small berries.

The figure B on the cloth-plate, back of the figures A, consists of similar curving tendrils with leaves set frequently thereon and bearing small berries.

35 The figures D D ornament the sides of the cloth-plate, and are composed of long slender stalks, around which twine numerous tendrils, which tendrils bear the same maple-like leaves and clusters of berries, the ends of the tendrils 40 of the figures D projecting toward each other near the middle of the cloth-plate.

The figures E E, which ornament the supporting-post of the needle-arm, at the front and the back thereof, are also composed of slender 45 tendrils bearing the maple-like leaves and berries above described, and running up and down the height of the post.

The figure F, which ornaments the supporting-post, on one side thereof, consists of similar leaves, tendrils, and berries running upward along the side of the post.

The figure G, ornamenting the side of the sewing-machine arm, is composed of two small tendrils, each bearing a leaf and berries, and situated at opposite ends of the inscription 55 "Eldredge," or other inscription placed against the side of the sewing-machine arm, on each side thereof.

The figure H, which ornaments the top of the needle-arm, on either side of a projecting 60 knob near the back thereof, is composed of slender tendrils bearing similar leaves and berries to those already described, and curving partly around said knob on each side.

I claim—

1. The design for the ornamentation of sewing-machines, consisting of the figure A, substantially as shown.

2. The design for the ornamentation of sewing-machines, consisting of the figure B, substantially as shown.

3. The design for the ornamentation of sewing-machines, consisting of the figure D, substantially as shown.

4. The design for the ornamentation of sewing-machines, consisting of the figure E, substantially as shown.

5. The design for the ornamentation of sewing-machines, consisting of the figure F, substantially as shown.

6. The design for the ornamentation of sewing-machines, consisting of the figure G, substantially as shown.

7. The design for the ornamentation of sewing-machines, consisting of the figure H, substantially as shown.

8. The design for the ornamentation of sewing-machines, consisting of the figures A, B, and D, substantially as shown.

9. The design for the ornamentation of sewing-machines, consisting of the figures E, F, G, and H, substantially as shown.

10. The design for the ornamentation of sewing-machines, consisting of the figures E and F, substantially as shown.

11. The design for the ornamentation of sewing-machines, consisting of the figures A, B, D, E, F, G, and H, substantially as shown.

WILLIAM HAEHNEL.
